Inventor
William W. Macfarlane
By his Attorney
F. W. Keeler

UNITED STATES PATENT OFFICE.

WILLIAM W. MACFARLANE, OF ELKINS PARK, PENNSYLVANIA, ASSIGNOR TO MACFARLANE COMMUNICATIONS CORPORATION, OF NEW YORK, N. Y., A CORPORATION OF DELAWARE.

TRAIN-CONTROL SYSTEM.

Application filed November 29, 1920. Serial No. 426,919.

To all whom it may concern:

Be it known that I, WILLIAM W. MACFARLANE, a citizen of the United States, and a resident of Elkins Park, county of Montgomery, and State of Pennsylvania, have invented certain new and useful Improvements in Train-Control Systems, of which the following is a specification.

The present invention relates generally to systems of train control and is more particularly an improvement on the inventions disclosed in applications Serial Number 203,378, filed November 22, 1917, now Patent No. 1,389,258, and Serial Number 372,440, filed April 9, 1920.

The main object of this invention is to dispense with the necessity of having a constant current flow in the traffic rails and also has for an object reducing the number of wires that are necessary in transmitting messages between a wayside station and a moving train or between two trains or between different ends of the same train.

In the application Serial No. 372,440, filed April 9, 1920, I disclosed means whereby a normally incomplete circuit is provided, which circuit is made complete by the train bridging the traffic rails; and also a local normally complete circuit. In the construction there shown, however, there was employed, in addition to the two line wires, a third line wire, and one of the main features of this invention is the elimination of this third line wire and the consequent cost thereof.

Other features will appear as the specification proceeds. In the accompanying drawings the invention is disclosed in several concrete and preferred forms in which—

Figure 1 is a diagrammatic view of the system showing one form of the invention.

Figure 2 is a diagrammatic view of a modified form of car-carried circuit.

1 and 2 indicate line wires paralleling the traffic rails 4 and 5. Wayside stations or central offices 6 are connected with line wires 1 and 2 at suitable intervals, say of one hundred miles. One rail 5 of the traffic track is divided by suitable insulation 7 into blocks or sections of suitable length depending upon the local traffic conditions and other circumstances, as will be understood. 8 and 9 indicate two wires connected with

line wires 1 and 2 and with rails 4 and 5. 55 A shunt 10 is connected between 8 and 9, said shunt being normally ruptured by armature 11 under the control of magnet 12, said magnet 12 constituting the core of a transformer winding 13 in inductive relation to winding 14 of wire 8. Conductor 8 is a part of a local and normally complete circuit consisting of said conductor rail 4, conductor 15 and line wire 2. Conductors 8 and 9 constitute two branch wires connected to 60 opposite rails, but not bridging them, and also connected to line wires 1 and 2, and wire 15 is a third branch wire that extends between rail 4 and line wire 2, which is the same rail and the same line wire with which 65 branch wire 8 is connected.

17 indicates the car having a winding 18 in circuit with rail 4 and in inductive relation to telephone circuit 19 having battery 20 and provided with the usual sending and 70 receiving devices as shown. As disclosed in said Patent No. 1,389,258 said winding 18 has an extremely low resistance.

The wayside station has a local circuit that may be traced as follows: from battery 80 21 by way of transmitter 22, conductor 23, key 24 (when depressed), conductor 25, transformer winding 26 and conductor 27, back to battery 21. The fluctuating speech current set up in transformer winding 26 85 induces a similar current in transformer winding 28, that flows by way of conductors 29 and 30, key 31 and conductor 32 to the line wires. From the line wires the current flows by way of branch wire 9 and 90 winding 13 to rail 5, thence across the car (if one be present) to rail 4, and then by way of wire 15 to line wire 2. Energization of transformer coil 13 induces a current in coil 14, which flows by way of conductor 8 95 to rail 4, winding 18 on car, rail 4, conductor 15, line wire 2 and conductor 8, back to winding 14. This induces a current in the local telephone circuit of the transformer winding of the car. A speech current generated in the car will be transmitted to the line wires and coil 28 over the circuits previously described, and button 24, now being elevated, current will pass from coil 26 to receiver 33 as follows: from coil 26 100 to wire 34, including receiver 33, to button 24, and thence by conductor 25 back to coil 26. 105 The foregoing description of the circuits

assumes that the train is travelling from right to left and is in advance of conductor 15 and behind conductor 8, but it will be evident that if the train is in advance of conductor 8 and behind conductor 15, then current flows to or from winding 18 of the train between the conductor 8 in rear of train and the conductor 15 in front of the train.

- 10 In case the attendants of two trains wish to speak with each other, the current will pass from the train in one block over the local circuits, as previously described, to the line wires, and thence to the local circuits of the block occupied by the other train. This circuit will be as follows: from coil 18 of car at right hand side of Fig. 1, to rail 4, thence by conductor 15 to line wire 2, conductor 8, rail 4 and back to winding 18. This induces a current in coil 13 which passes over conductor 9, rail 5, car 17, rail 4, conductor 15, line wire 2, conductor 15 at left hand side of Fig. 1, rail 4, car 17, conductor 9, line wire 1, conductor 9 at right hand side Fig. 1, back to coil 13. This in turn induces a current in coil 14 at left hand side of Fig. 1, which passes by way of conductor 8 to rail 4, coil 18 conductor 15, line wire 2, conductor 8 and back to coil 14.
- 20 The same thing will occur when attendants at opposite ends of a train occupying more than one block wish to speak with each other, but if the train is entirely within the same block, the current may flow along the 25 rail from one winding 18 to another without going over the line wires, and the circuit would then be as follows: from winding 18 of one car along rail 4 to winding 18 of another car, across car to rail 5, along rail 30 5 to first car, across the first car to rail 4.

To give a signal, either audible or visual or both, along the line of way, to indicate to the attendant of a train that the train dispatcher desires to communicate with him, 35 means are employed for energizing coil 12 sufficiently to attract armature 11, thereby closing shunt 10 and illuminating light 35, or ringing a bell, or the like. This is accomplished by depressing key 31, thereby 40 placing a powerful source of current, here shown as battery 21, in circuit with line wires 1 and 2 and establishing a circuit as follows: from battery 21 to key 31, conductor 30, to line wire 1, by way of conductor 55 9 and coil 13, rail 5, car 17, rail 4, conductor 8 and coil 14 to line wire 2, and by wire 37 back to battery 21.

In describing the local wayside station, mention has been made of key 24, which is 60 depressed and raised in a manner well understood to cut in and out the receiving and transmitting circuits, and it will be understood that in accordance with well-known practice and as described in the applications 65 previously referred to, such device might

be used in connection with the local circuit 19 on the train or car. In order to obviate the necessity of depressing the button and releasing it to cut in and out the transmitting circuits of the train, to enable the operator to hear and speak at the same time, recourse may be had to the construction shown in Figure 2 which is intended to be used in the system previously described. As shown in this figure, the car-carried circuit 70 consists of separate transmitting and receiving circuits 40 and 41, and in these circuits are included what may be called secondary windings 42 and 43. What may be called primary windings 44 and 45 are connected 75 in parallel as shown and are both connected with the body of the car and thereby to the rail, as will be understood. Preferably, number 46 is a copper bar or cable of very 80 low resistance.

An illustration of the relative resistance of the wiring shown in Fig. 2 is as follows: The copper bar 46 has a value which may be designated as one million circular mills. This, however, does not include the 90 winding 44 which may consist of seventy turns of No. 2 double cotton covered wire. Winding 43 may consist of three thousand turns of No. 29 wire. Winding 45 may be three hundred seventy-two turns of No. 22 95 wire and the wire by means of which this winding is connected to the copper bar may be No. 16 wire. Winding 42 may be eighteen hundred turns of No. 20 wire. The resistance value of each rail of the track 100 may be considered as being eight hundred thousand circular mills or one million six hundred thousand circular mills for both rails. It will now be understood that the current that will be diverted from the rail 105 through copper cable 46 and winding 44 will prefer this path to that including the winding 45 which latter is of a very much higher resistance than 44 and 46 and that in impressing current from the circuit containing winding 42 the bulk of it will naturally pass through the rails because their resistance is lower than that of the path produced by 44 and 46, but sufficient current 110 is shunted through 44 and 46 to operate the 115 receiver.

I claim:

A system of the character described comprising: two line wires, traffic rails, two branch wires connected to the line wires and connected to, but not bridging, the rails, a third branch wire extending between one of the line wires and one of the rails and forming with one of the two first branch wires with one of the line wires and with one of the rails a normally incomplete circuit, said third branch forming with the other of said two first branch wires with one of the line wires and with one of the rails a normally complete local circuit, an inductive 120 125 130

coupling between the two first branch wires, a car for completing the normally incomplete circuit by bridging the rails, means on the car responsive to current in the local circuit and for impressing current on said local circuit, and a wayside station responsive to current impressed by the local circuit upon the line wires, and for impressing current on the line wires to energize the local circuit.

¹⁰
Signed at Elkins Park, in the county of Montgomery and State of Pennsylvania, this 15th day of Nov., 1920.

WILLIAM W. MACFARLANE.
